UNITED STATES PATENT OFFICE.

JAMES C. ARMSTRONG, OF BELOIT, WISCONSIN.

COOLING SYSTEM FOR INTERNAL-COMBUSTION ENGINES.

Application filed February 3, 1920. Serial No. 356,085.

To all whom it may concern:

Be it known that I, JAMES C. ARMSTRONG, a citizen of the United States of America, and a resident of Beloit, county of Rock, 5 and State of Wisconsin, have invented certain new and useful Improvements in Cooling Systems for Internal-Combustion Engines, of which the following is a specification.

10 This invention relates to internal combustion engines, and especially to cooling means therefor. Various means have heretofore been employed to cool engines of this character, including water jackets connected either to open tanks or to water mains, and also various forms of air cooled water radiators.

15 The main objects of this invention are to provide means of improved form and greater efficiency for cooling the cylinders of internal combustion engines; to provide for water jacket protection of the combustion cylinders without the loss of water and consequent need of replenishment; to provide 20 for positive condensation of all vapor and steam generated by the heat transmitted to the water and for the immediate return of the water of condensation to the tank or jacket; and to provide for air-cooling of 25 the condensation chamber used in connection with the water jacket and tank; to maintain a constant temperature of the engine cylinder walls during operation, to protect the radiator from freezing and damage, and to obviate the use of a circulating 30 pump.

35 An illustrative embodiment of this invention is shown in the accompanying drawings, in which—

40 Fig. 1 is a vertical section along the axis of the engine cylinder, as at 1—1 on Fig. 2.

Fig. 2 is a vertical cross-section along the axis of the fan and crank shaft, as at 2—2 on Fig. 1.

45 Fig. 3 is a fragmentary view showing a front elevation of the fan and associated parts.

Fig. 4 is a side view of the jacket tank showing the water gage.

50 Fig. 5 is a fragmentary view of a vertical section at the line 5—5 of Fig. 4.

Fig. 6 is an enlarged fragmentary section of the condenser at 6—6 on Fig. 2.

55 Fig. 7 is an enlarged fragmentary elevation view of the condenser as seen in Fig. 1.

Fig. 8 is a horizontal section through part of the condenser plates at line 8 on Fig. 7.

Fig. 9 is a plan of part of a stamped condenser plate ready for assembling with others.

In the construction shown in the drawings, the engine frame 1 is provided with an internal combustion cylinder 2, a water jacket 3 surrounding said cylinder, and a reservoir or tank 4 directly above and communicating with said jacket.

Mounted on said frame 1 is an air-cooled condenser or radiator 5 in the form of a multi-perforated steam condenser. There is also a fan 6 provided with an air flue 7 communicating with said radiator. Said fan is concentric with the crank shaft 8 and is supported thereon, as will be more fully described, by means of the pulley or fly wheel 9 which is keyed to the end of said 75 shaft, as indicated at 8' on Fig. 3. A fly wheel 10 is mounted on the opposite end of said shaft from said pulley.

The jacket chamber 3, at its upper side, communicates directly with the interior of 80 tank 4, as shown at the point 11 on Fig. 1. Extending from the upper part of the chamber 4' in said tank is a horizontal steam passageway 12 leading forward to a point over the crank shaft 8 and turning upward 85 to communicate with the radiator 5.

A water supply inlet is provided at 13 on the upper side of the tank 4 and sufficient water is supplied initially to about half fill the chamber 4', the normal level being indicated at the line 14 on Fig. 1. Under normal conditions of operation, condensation strikes such a balance with evaporation that there is no leakage of steam from the device, as will be more fully explained. 90 Hence, the water level remains substantially constant without any attention from the person in charge of the engine, but in order to provide a ready means to indicate the height of the water in the tank, a water 100 gage 15 is provided in a recess in the side of the tank, the wall being depressed at this point, as shown at 15', and the gage being disposed in alignment with the aperture at 13, as illustrated in Figs. 4 and 5. 105

The radiator 5 comprises a rectangular frame 16 formed nearly square and stood on edge, the radiator being relatively thin from front to back. Enclosed by said frame is a multiperforate body part 17 adapted to 110

transmit the air from said flue 7 at the right of Fig. 2 to the back or discharge side at the left. Said body part 17 is substantially a laminated structure, including a series of 5 thin corrugated or stamped metal sheets 18 connected in pairs and arranged to form vertical passageways 19 of a broad and thin wavy shape for the steam and water of condensation, and also to form horizontal 10 flues 20 for the fan driven air. Each sheet includes a series of parallel strips or zones 21, which are substantially flat, interposed with the corrugations or ribs 22 in the form of semicylindrical grooves disposed horizontally. The corrugations of one pair 23 of plates are staggered with respect to those of the next adjacent pair 24, as shown in Figs. 6 and 7, so that the aperture 19 may be of approximately uniform thickness. 15 20 The vertical edges of the plates of each pair are fastened fluid-tight to the contiguous edges of the plates of the adjacent pairs, as at 22' on Figs. 8 and 9, solder being suitable for the purpose.

25 The precise shape or size of the resulting tubular apertures 20 is not important, but it is essential for the intended normal operation of the radiator that the steam spaces 19 between plate pairs 23 and 24 shall be 30 so small as to permit effective operation of water surface tension so as to provide sufficient capillary effect to maintain a film or substantial wall of water across the vertical passageway, so as to prevent the free 35 escape of steam. Under normal operating conditions, the passages 19 are substantially filled with water for a considerable height, and it is found by pressure gage tests that, by reason of this water head or plug in 40 the steam apertures 19, there is normally maintained in the tank 4 a sufficient pressure to produce a gage reading of approximately one-half pound per square inch. The water head or level in the condenser is indicated at 19' on Fig. 1.

In order to accommodate the release of any possible excess of pressure in the radiator, as in case of a continued overload, or failure of the fan, a vent aperture 25 is 50 provided in the top, as shown in Fig. 1. The top part or cover 26 of the condenser device, is preferably detachable and adapted for ready removal if desired. A clearance space 27 is provided beneath said cover. 55 The reason for the advanced position of the condenser 5 directly over the crank shaft and in the vertical plane of the fan axis, is to provide a most direct line of draft upward and backward from the fan 60 to the condenser.

The fan 6 comprises a back plate or disk 28 having a peripheral series of radially disposed vanes 29 on its front side and perpendicular thereto. Said plate 28 is secured to the back side of the pulley 9 by

means of arms or brackets 30 fastened to the arms 9' of the open spider of said pulley. An aperture 31 is provided in the middle of said plate 28 so as to clear the adjacent journal bearing 32 of shaft 8. 70 The vanes 29 are triangular and diminish in size toward the center of disk 28. Each vane is secured by means of an upturned flange 33 disposed against the face of said plate. The main features of this fan are 75 set forth and claimed in my copending application Serial No. 356,086, filed of even date herewith.

The walls 34 and 35 of flue 7 are formed to provide a smoothly curved direct path 80 to the condenser 5. The front wall 34 is apertured at 36 to admit air to the fan. The rear wall 35 has an aperture to provide clearance respecting bearing 32.

In the embodiment here shown, the engine 85 frame 1 is adapted to rest on the floor or on a permanent foundation, as may be required for large units, as will be understood without specific illustration. It is not intended to imply, however, that this invention is 90 limited to such units or to engines having this style of frame or means of support.

The arrangement of the radiator and inherent drainage thereof results in protection from freezing and damage by collision, less 95 cost, less weight. The use of fan on the crank shaft does away with fan belt and bearing maintenance cost and unreliability. A controllable source of heat for closed cars is furnished by the hot air discharged from the 100 fan. Satisfactory operation resulting from this device of the automobile and trucks and tractors and farm engines will increase their use during winter months.

Although but one specific embodiment of 105 this invention has been herein shown and described, it will be understood that numerous details of the construction shown may be altered or omitted without departing from the spirit of this invention as defined by the 110 following claims.

I claim:

1. In combination, a source of heat, a water jacket therefor, a reservoir disposed above and communicating with said water jacket, and a condenser disposed to drain into said reservoir and communicating upwardly with the atmosphere.

2. In combination, a source of heat, a water jacket therefor, a reservoir disposed above and communicating with said water jacket, an air cooled atmospheric-pressure steam condensing radiator having narrow passage-ways adapted for closure by operation of the surface tension of water and disposed to drain into said reservoir and communicating upwardly with the air.

3. In combination, an internal combustion chamber a water jacket therefor and a condenser disposed above and communicating 130

with said water jacket said condenser having alternately disposed air passages and capillary apertures, the latter being for steam and water of condensation.

5 4. In combination, an internal combustion chamber a water jacket therefor, a condenser disposed above and communicating with said water jacket, said condenser having alternately disposed air passages and capillary 10 apertures, the latter being for steam and water of condensation, and means to drive a blast of air through said air passages.

5. In combination, a source of heat, a water jacket therefor, and a condenser communicating therewith, said condenser including a plurality of capillary apertures of upwardly extending wavy character with interposed horizontal air passages in staggered mutual relation.

20 6. In combination, an internal combustion chamber, a water jacket therefor, and a condenser disposed above and communicating with said water jacket, said condenser having alternately disposed air passages and 25 capillary apertures, the latter being for steam and water of condensation, and said condenser comprising a plurality of thin metallic sheets enclosing said capillary apertures which open downwardly into said 30 steam jacket and which open upwardly to the atmosphere.

7. An internal combustion engine, provided with a water jacket for cooling the cyl-

inder, and a condenser disposed above and communicating with said jacket, said condenser being provided with a plurality of upwardly extending narrow passageways communicating with the atmosphere, said passageways being formed and arranged to drain any surplus of the condensed fluid 40 back into the water jacket and also to retain more or less of the water of condensation by virtue of capillarity, whereby a substantial pressure may be maintained within said device.

45 8. An internal combustion engine provided with a water jacket for the cylinder and a condenser disposed above and communicating with said water jacket, said condenser including a plurality of upwardly extending passageways wherein the steam may be condensed and held by surface tension and capillarity, the upper ends of said passageways being open to the atmosphere.

9. An internal combustion engine having 55 a horizontally disposed cylinder, a water jacket therefor, a crank shaft, a condenser disposed over said crank shaft, a passageway extending upwardly and forwardly from said water jacket to said condenser, a 60 fan coaxial with and carried by said crank shaft, and a guide flue leading upward and backward from said fan to said condenser.

Signed at Chicago this 24 day of Jan., 1920.

JAMES C. ARMSTRONG.
